UNITED STATES PATENT OFFICE.

WILLIAM H. ROBBINS, OF SPRINGFIELD, OHIO, ASSIGNOR TO THE WILLIAMS COMPANY, OF LONDON, OHIO, A CORPORATION OF OHIO.

STEEL-WOOL ABRASIVE FABRIC.

Application filed February 4, 1927. Serial No. 168,000.

My invention relates to steel wool and particularly to belts and fabrics made therefrom, with and without other materials.

It is the object of my invention to provide 5 polishing and abrading belts, ropes and other forms and shapes of steel wool either in combination with or without other materials, such as polishing and absorbing materials.

Referring to the drawings, 10 Fig. 1 is a perspective view of a composite belt woven into a fabric, such belt being composed of steel wool and textile material;

Fig. 2 is a plan view of such fabric composed 15 of threads in one direction of textile material such as yarn, and in the other direction threads of steel wool;

Fig. 3 is a section through such a fabric;

Fig. 4 is a section through a fabric so arranged that the textile material is on the outside 20 and the steel wool is on the inside for furnishing the strength of the material;

Referring to the drawings in detail 1 indicates the steel wool strands which are not absorbent, rough and abrasive, while 2 designates a textile strand such as yarn which is 25 soft, capable of polishing and is absorbent. It is desirable according to the type of work to be performed to arrange the steel wool strands so that they form the major portion of the 30 surfaces as in Figures 2 and 3, or the textile strands so that they form the major portion of the surface as in Fig. 4 if the primary object is polishing.

As shown in Fig. 1 a belt either of steel wool by itself or in combination with the textile material as shown in Figures 3 and 4 may be employed. This flat belt which is designated generally 4 is mounted upon the drums 5 which are suitably actuated so that a broad 35 polishing belt is provided for polishing the 40 surface 6.

It will be understood that I desire to comprehend within my invention such modification within the scope of the claims as may be necessary to adapt it to varying conditions and 45 uses.

Having thus fully described my invention, what I claim as new and desire to secure by Letters Patent, is:—

1. A new article of manufacture for polishing such as a fabric composed of woven steel wool and textile strands. 50

2. A new article of manufacture for use as a belt consisting of woven steel wool and textile strands. 55

3. A new article of manufacture such as an endless relatively broad belt woven of steel wool and textile strands.

4. A new article of manufacture consisting of a woven fabric formed of steel wool and textile strands, the steel wool strands forming the exposed surface of the fabric while the textile strands are concealed therein. 60

In testimony whereof, I affix my signature.

WILLIAM H. ROBBINS.
